MEANS FOR CONTROLLING VOLUME RANGE.

Application filed December 18, 1924. Serial No. 755,768.

This invention relates to transmission circuits, and particularly to arrangements for enabling such circuits to transmit a wider range of volume than they are normally capable of handling.

The range of volume which ordinary circuits will handle is limited principally by two factors, — (1) if the volume is allowed to fall below a certain value, noise and cross-talk interference from adjacent circuits becomes objectionable, and (2) if the volume is permitted to increase above a maximum value, cross-talk will be introduced into adjacent circuits working at a lower energy level, and also distortion will be introduced due to overloading of repeaters.

In connection with radio broadcasting and public address systems where the material must be transmitted to a distant point, the range which it is desirable to transmit is considerably wider than the above conditions will permit. While it would be possible to increase the volume range by more careful line construction and the use of high power repeaters, the expense of this course of procedure would be prohibitive. It is proposed by the present invention to permit the transmission of a volume range wider than that to which a given transmission circuit is limited by increasing or decreasing the volume applied to the circuit whenever it is lower or higher than the limits of the circuit, at the same time producing a complementary adjustment at the receiving end of the circuit so that the volume impressed upon the receiver will be the same as it would have been if no volume control whatever had been exercised. This is accomplished by providing an adjustable switch which, in response to any change in its adjustment, causes the transmission of controlling impulses from the transmitting end of the system to the receiving end. At each end of the system gain control adjustments are made simultaneously in response to the impulses, these adjustments being complementary to each other, so that if the volume is increased at the transmitting end it will be decreased at the receiving end, and vice versa.

The invention will now be more fully understood from the following detailed description thereof when read in connection with the accompanying drawing, the figure

of which illustrates a preferred embodiment of the invention.

Referring to the drawing, the apparatus at the transmitting end of the circuit is illustrated at the left, and the corresponding apparatus at the receiving end of the circuit is illustrated at the right. ML designates the transmission line over which the energy is to be transmitted. In order to control the volume applied to the line ML, a vacuum tube amplifier A is provided having a potentiometer P whose adjustment may be varied by means of a series of relays E₀ to E₁₁, inclusive. At the receiving station a similar vacuum tube amplifier A' is interposed between the main line ML and the receiver to produce complementary adjustments in the transmission. The gain of this amplifier is determined by a potentiometer whose setting is controlled by a series of relays E'₀ to E'₁₁, inclusive. The potentiometer P is so arranged that as successive E relays are operated from left to right the gain of the amplifier A is increased; the potentiometer P', on the other hand is so arranged that as its successive E' relays are operated from left to right the gain is decreased.

In order to control the setting of the two potentiometers, a rotatable switch S may be provided having switch arms 20 and 21 which may be made to contact with any one of a series of contacts or segments arranged in the form of a semi-circle. If, when the arms of the switch are resting upon any pair of contacts, the switch arms are moved to other contacts, impulses are transmitted over auxiliary telegraph circuits L and L'. These telegraph circuits are illustrated for convenience as being separate circuits from the conductors of the main transmission line ML, but it will be understood that they may be the Morse legs obtained by compositing the line ML, or they may be phantom circuits, or any other type of telegraph circuits available in the plant.

A series of differential stepping relays C₁, C₂, etc., and a corresponding series of stepping relays D₁ and D₂, whose windings are aiding are provided at the sending station. Corresponding stepping relays C'₁, C'₂, etc., and D'₁, D'₂, etc., are provided at the receiving station. The two sets of stepping relays at the two stations are arranged

to be operated in response to the impulses transmitted from the telegraph lines to determine the adjustment of the potentiometers P and P', respectively, under control of the 5 E and E' relays. Further details of the invention may now be understood from a description of the operation, which is as follows:

Assuming that the switch S has its arms 10 20 and 21 in the position shown in the drawing, that is, resting upon the O contacts, the circuits will be in the condition illustrated with none of the stepping relays operated at either station. Under these 15 conditions relays E_o at the transmitting station and the relay E_o' at the receiving station will be energized, the other E relays being deenergized so that the grid of the amplifier A is connected to the lowest point of the 20 potentiometer P corresponding to the position of lowest gain of the amplifier. At the receiving station, however, the grid of the amplifier A' will be connected to the highest point of the potentiometer P' corresponding 25 to the condition of maximum gain of the amplifier.

Suppose, now, the switch arms 20 and 21 of the switch S are moved in a clockwise position from the O contact to, say, contact No. 3 of the switch. When the switch arms rested on the O contacts, relays X and Y were deenergized by reason of the short-circuiting of their windings. The short-circuit for the relay X extends from 30 the terminal of its winding over the segment 22 of the switch and arm 20 to the grounded O contact. The short-circuit for the relay Y, on the other hand, extended from the terminal of its windings over the segment 35 23 of the switch, arm 21, O contact, over conductor Y_o, and over the lower back contact of relay C₁. As soon as the switch arms 20 and 21 were moved from the O contacts, both of these ground connections were 40 broken, and the short-circuits about the windings of relays X and Y were open. These relays are at once energized thereby completing a circuit from battery, through the winding of relay 24, front contacts of 45 relays X and Y, back contact of relay 50 27, and over the back contact of relay 26 to ground. The relay 24 is energized and opens the circuit of the telegraph line L so that an open circuit impulse is transmitted 55 causing the release of relay 28 at the transmitting station and relay 28' at the receiving station.

Relay 28, upon being deenergized, connects ground to the up-conductor 30 so that 60 a circuit is completed over conductor 30 and over the lower back contact of relay D₁, through the lower winding of relay C₁ to battery. At the same time a circuit is completed over the back contact of relay 28 for 65 the relay 26. Relay C₁, upon being ener-

gized, at its lower contact shifts the ground from conductor Y_o to conductors X₁ and Y₁ so that ground is now applied to the two contacts numbered 1 of the switch S. Relay 26, upon being energized, opens the circuit previously traced for the relay 24 so that the circuit through the line L is again closed and the open circuit impulse ceases. Relays 28 and 28' are energized, disconnecting ground from up-conductors 70 75 30 and 30', respectively.

Upon ground being disconnected from conductor 30, a short-circuit is removed from about the lower winding of relay D₁, and relay D₁ is accordingly energized over 80 a circuit through the lower windings of relays C₁ and D₁ in series to ground over the upper front contact of relay C₁. Relay D₁, upon being energized, opens the normal circuit for the relay E_o at its upper back 85 contact and closes the circuit of relay E₁ at its upper front contact. Relay E_o disconnects the grid of the amplifier A from the point O of the potentiometer while relay E₁ connects said grid over its front contact to the point 1 of the potentiometer P. 90

At the receiving station a similar operation takes place. Upon the release of relay 28' at the beginning of the open circuit impulse, ground was connected to conductor 95 30' thereby energizing relay C₁' through its lower winding. At the end of the impulse the ground connection of conductor 30' is broken so that a circuit is established in series through the lower windings of 100 relays C₁' and D₁' to energize relay D₁' and maintain both relays locked up. Relay D₁' at its upper contact opens a normally energizing circuit of relay E_o' and closes the circuit of E₁'. The release 105 of E_o' disconnects the grid of the amplifier A from the O point of the potentiometer (corresponding to maximum gain), and relay E₁' at the same time connects said grid 110 to the point 1 of the potentiometer P'. Consequently the gain of the amplifier A at the sending station is increased one step, and the gain of the amplifier A' at the receiving station is decreased a corresponding 115 step.

At the end of the transmission of the open circuit impulse over line L the energization of the relay 28 resulted in opening the ground connection to the winding of relay 26 at the same time that it removed the ground from the up-conductor 30. Relay 26 accordingly is released, and as the short-circuiting ground connections are not yet established, relays X and Y of the original circuit through the relay 24 is again completed. Relay 24 now opens the circuit of the line L to transmit another open circuit impulse through the relays 28 and 28'. Relay 28 again connects ground to the up-conductor 30 and to the relay 26. The 120 125 130

ground connection over conductor 30 is now established over the lower make contact of relay D_1 and over the lower back contact or relay D_2 and then through the lower winding of relay C_2 to battery. Relay C_2 upon being energized disconnects at its lower armature the ground connection over conductor Y_1 and connects ground to conductors X_2 and Y_2 . The ground still remains connected to conductor X_1 over the lower front contact of relay C_1 . As a result of this operation, ground is now applied to contacts 0, 1 and 2 of the upper group and to contact 2 of the lower group.

15 Relay 26, which was energized as a result of the beginning of the second open circuit impulse again opens the circuit of the relay 24 which, in turn, permits its armature to fall off and close a circuit through the line 20 L , thus terminating the second open impulse and causing the energization of relays 28 and 28'. Relay 28 disconnects ground from conductor 30 thereby removing the short-circuit from about the lower winding of 25 the relay D_2 so that said relay is energized over a circuit through the lower winding of relay C_2 and lower winding of relay D_2 and thence over the upper front contact of relay C_2 to ground. Both relays are locked up 30 over the circuit thus traced. Relay D_2 , upon being energized, at its upper front contact opens the circuit of relay E_1 and closes the circuit of relay E_2 , thus connecting the grid of the amplifier A to the second 35 point of the potentiometer, instead of the first point.

At the receiving station relay 28' was released at the beginning of the second open circuit impulse thereby connecting ground 40 to conductor 30' and over the lower front contact of lock-up relay D'_1 and thence over the lower back contact of relay D'_2 and through the lower winding of relay C'_2 to battery. Relay C_2 is accordingly energized.

45 At the end of the open circuit impulse the ground connection is removed from conductor 30' thereby removing the short-circuit from the lower winding of relay D'_2 so that relay D'_2 is energized and relays C'_2 and D'_2 are locked up over their lower windings in 50 series with each other. Relay D'_2 , upon being energized, opens the circuit of relay E'_1 at its upper contact and closes the circuit of relay E'_2 . The grid of the amplifier A' is now connected to point 2 of the 55 potentiometer P' instead of to the point 1. Consequently the gain of the amplifier A' has been decreased two steps simultaneous with the corresponding increase of the gain 60 of the amplifier by two steps.

Returning to the transmitting station, it will be recalled that at the end of the second open circuit impulse ground was disconnected from the winding of relay 26 so that 65 said relay was deenergized. Short-circuit-

ing grounds are not yet connected at this time to the windings of relays X and Y and consequently the deenergization of relay 26 again completes the circuit through relay 24. The energization of relay 24 opens the 70 circuit of the line L thereby causing the deenergization of relays 28 and 28'. Relay 28 again connects ground to relay 26 and to up-conductor 30 so that from the conductor 75 30 a circuit is established over the lower front contacts of relays D_1 and D_2 and over the lower back contact of relay D_3 and through the lower winding of relay C_3 to battery. Relay C_3 is energized and at its lower contact disconnects ground from conductor Y_2 and connects ground to conductors X_3 and Y_3 over the connections of the succeeding relay C_4 (not shown). Ground is now applied to contacts 0, 1, 2 and 3 of the upper group and to contact 3 of the lower group of switch S . Relays X and Y are at once short-circuited by the ground connections established over the switch arms 20 and 21 so that said relays are released. The energization of relay 26, in response to 80 the initiation of the open circuit impulse, opens the circuit of the relay 24 which will now remain open at the contacts of relays X and Y . Relay 24 again closes a circuit through the line L and ends the third open 85 circuit impulse. Relays 28 and 28' are again energized, the former relay disconnecting ground from relay 26 and from conductor 30. The disconnection of ground from conductor 30 removes the short-circuit from 90 about the lower winding of the relay D_3 so that relays C_3 and D_3 are locked up in series through their lower windings. Relay D_3 , in turn, opens the circuit of relay E'_2 and closes the circuit of the relay E'_3 thereby 95 connecting the grid of the amplifier to the third point of the potentiometer P .

Returning to relay 26, it will be noted that at the end of the third open circuit impulse the said relay was again deenergized. The deenergization of this relay does not again cause the energization of relay 24 by reason of the fact that relays X and Y are now short-circuited to maintain the circuit of said relay open. Consequently no more impulses are transmitted over the line L .

At the receiving station the relay C'_3 was energized at the beginning of the open circuit impulse when ground was connected to the up-conductor 30'. At the end of said impulse relays C'_3 and D'_3 are locked up in series, the energization of the latter causing the circuit of relay E'_2 to be opened and the circuit of E'_3 to be closed thereby connecting the grid of the amplifier A' to the third point of the potentiometer. Consequently at the end of the third impulse the gain of the amplifier A was increased a third step and the gain of the amplifier A'

- was simultaneously decreased a third step. It will therefore be clear that in response to the setting of the switch S simultaneous and complementary adjustments of the volume were made at the transmitting and receiving ends of the line ML . In other words, the volume was increased at the transmitting end and correspondingly decreased at the receiving end.
- 10 Suppose, now, with the circuits in the condition just described, the arms 20 and 21 of the switch S are moved in a counter-clockwise direction and permitted to rest on contacts 1-1 of the switch. It will be remembered that the energization and locking up of the relays C_1 , C_2 and C_3 did not remove ground from contacts 1, 2 and 3 of the upper group, and as ground is permanently applied to the O contact, these four contacts of the upper group will all be connected to ground at this time. The moving of the switch arm 20 to the first contact therefore does not remove the short-circuiting ground from the relay X . In the condition of the counting relay circuits at the time they were last described ground was applied to the third contact of the lower group over conductor Y_3 due to the energization of relay C_3 . Ground had been disconnected, however, from contacts 0, 1 and 2 of the lower group. Consequently, when the switch arm 21 is removed to contact 1 of the lower group the short-circuiting ground is disconnected from the relay Y and said relay is energized.
- The energization of the relay Y completes a circuit from ground, over the lower contact of relay 26, back contact of relay 27, front contact of relay Y , back contact of relay X , and through the winding of relay 25 to battery. Relay 25 is energized and opens the circuit of line L' thereby initiating an open circuit impulse causing the release of the line relays 29 and 29'. The deenergization of line relay 29 connects battery to relay 27 and to the down-conductor 31. A circuit is thereby completed over conductor 31, over the innermost upper back contact of relay D_{11} , over corresponding contacts of other counting relays (not shown), and thence over the innermost front contact of counting relay D_2 , through the upper winding of said relay, and through the upper winding of relay C_3 to ground. The windings of the D relays are aiding, but the windings of the C relays are differential. Consequently the circuit just traced results in the deenergization of relay C_3 . Relay C_3 disconnects ground from conductors X_3 and Y_3 and connects ground to conductor Y_2 . At its upper contacts relay C_3 also connects a ground to the lead between the upper winding of relay D_3 and the upper winding of relay C_3 . This prevents the operation of relay C_3 through its upper winding after the circuit of the lower winding has been broken.
- 15 While these operations were taking place, the relay 27 was energized upon the initiation of the open circuit impulse, and at its upper contact opens the circuit previously traced through the winding of relay 25. Relay 25 releases its armature and again closes a circuit through the line L' , thus terminating the open circuit impulse. Relays 29 and 29' are accordingly energized and disconnect battery from the upper conductors 31 and 31'. The disconnection of battery from the conductor 31 causes the current to cease flowing through the upper windings of relay D_3 and C_3 . The previous release of relay C_3 having already opened the circuit of the lower winding of relay D_3 , relay D_3 is accordingly deenergized thereby extending the conductor 30 to the innermost upper armature of relay D_2 . At its upper contact relay D_3 opens the circuit of relay E_3 and closes the circuit of the relay E_2 , thus shifting the potentiometer connection to the second point and decreasing the gain of the amplifier one step.
- 20 Simultaneously with the operations described at the transmitting station similar series of operations took place at the receiving station. At the beginning of the open circuit impulse, relay 29' released its armature and connected battery to the upper conductor 31 thereby completing a circuit over the innermost upper contact of relay D_{11} , and over the contacts of succeeding stepping relays (not shown) and thence over the innermost upper front contact of relay D_3' , through the upper windings of relays D_3' and C_3' to ground. Relay C_3' being differential is deenergized and opens the locking circuit through the lower winding of relay D_3' , the relay D_3' being maintained energized, however, through its upper winding. At its upper contact relay C_3' also connects a ground to the lead between the upper winding of relay D_3' and the upper winding of relay C_3' . This prevents the operation of relay C_3' through its upper winding after the circuit through the lower winding has been broken.
- 25 At the end of the open circuit impulse, line relay 29' disconnects battery from the down-conductor 31' thereby opening the circuit through the upper winding of relay D_3' which is accordingly released. Relay D_3' at its uppermost contact opens the circuit of relay E_3' and closes the circuit of E_2' thereby shifting the potentiometer connections to the second point of the potentiometer. Consequently the gain of the amplifier A' is increased one step and that of the amplifier A is simultaneously decreased one step.
- 30 Returning to the transmitting station, it will be recalled that at the end of the first

open circuit impulse relay 29 disconnected battery from the relay 27. Relay 27 is accordingly deenergized and again completes the circuit of relay 25 (no short-circuiting 5 ground connection being yet established from the switch arm 21 for the relay Y). Relay 25 again opens the circuit of the line L' initiating a second open circuit impulse and causing the release of the line relays 29 10 and 29'. Battery is again connected to relay 27 and to conductor 31 so that a circuit is now established over the innermost upper contacts of relays D₁₁ and D₃ and over the innermost upper front contact of relay D₂ 15 and through the upper windings of relays D₂ and C₂ to ground. Differential relay C₂ is now released and the locking circuit through the lower winding of the relay D₂ is opened, relay D₂ being energized through 20 its upper winding. Relay C₂ upon being deenergized disconnects ground from conductors X₂ and Y₂ and connects ground to conductor Y₁ so that ground is now connected to the first contact of the lower 25 group of switch S. Consequently a short-circuit connection is established over the switch arm 21 for the relay Y which is accordingly released. The relay 27 upon being energized at the beginning of the open 30 circuit impulse opens the circuit previously traced for the relay 25. This circuit is now permanently maintained open due to the short-circuiting of the relay Y with the consequent release of the armature of said 35 relay. Relay 25 upon being released again closes the circuit through the line L₁' and energizes the relays 29 and 29'. Relay 29, upon being energized, disconnects battery from the relay 27 and from conductor 31. 40 Relay 27, upon being released, does not again establish the circuit of relay 25 due to the deenergization of relay Y. The disconnection of battery from conductor 31 causes the release of relay D₂ thereby opening 45 the circuit of relay E₂ and closing the circuit of relay A₁. The grid of the amplifier A is now connected to the first point of the potentiotmeter P.

As no further impulses are transmitted, 50 the circuit remains in the condition thus described with all of the counting relays released except relays C₁ and D₁. Ground is now connected to the contacts 0 and 1 of the upper group and to the contact 1 of the lower group of the switch S.

At the receiving end relay 29' is released 55 at the beginning of the second open circuit impulse thereby connecting ground to the down-conductor 31' to release the relay C₂'. At the end of the open circuit impulse, relay 29' was again energized, disconnecting battery from the down-conductor 31' thereby releasing the relay D₂'. The latter relay 60 opened the circuit of the relay E₂' and closed the circuit of the relay E₁' thereby

connecting the grid of the amplifier A' to the first point of the potentiotmeter P'. Consequently, as a result of the two impulses transmitted, the gain of the amplifier A' was increased two steps and that of the amplifier A decreased two steps simultaneously. The circuit remains with relays C₁' and D₁' locked up ready for any succeeding change in the setting of the switch S.

It will be obvious that the general principles herein disclosed may be embodied in many other organizations widely different from those illustrated without departing from the spirit of the invention as defined 70 in the following claims.

What is claimed is:

1. In a transmission system, a transmission medium interconnecting two stations, volume adjusting means at each station, a manual control switch at one of said stations, means operated by any degree of change in the setting of said switch to transmit impulses between said stations, the number of impulses transmitted being determined by the change in the setting of said switch, and means responsive to the transmission of said impulses to cause simultaneous and complementary adjustments of the volume at the two stations.

2. In a transmission system, a transmission medium interconnecting two stations, volume adjusting means at each station, a manual control switch at one of said stations, means operated by any degree of change in the setting of said switch to transmit impulses between said stations, the number of impulses transmitted being determined by the change in the setting of said switch, and step-by-step means responsive to the transmission of said impulses to simultaneously effect complementary step-by-step adjustments of the volume at the two stations.

3. In a transmission system, a transmission medium interconnecting two stations, volume adjusting means at each station, a manual control switch at one of said stations, means operated by any degree of change in the setting of said switch to transmit impulses between said stations, the number of impulses transmitted being determined by the change in the setting of said switch, sets of counting relays at each station responsive to the impulses transmitted to produce simultaneously complementary step-by-step adjustments of the volume at the two stations.

4. In a transmission system, a transmission medium interconnecting two stations, volume adjusting means at each station, a manual control switch at one of said stations, means operated by any degree of change in the setting of said switch to transmit impulses between said stations, the num-

- ber of impulses transmitted being determined by the change in the setting of said switch, sets of counting relays at each station, said counting relays being successively operated in one order at both stations in response to impulses resulting from adjustment of said switch in one direction and being successively operated in a reverse order in response to impulses resulting from an adjustment of said switch in the opposite direction, said counting relays producing simultaneously complementary step-by-step adjustments of volume at the two stations.
5. In a transmission system, a transmission medium interconnecting two stations, means for adjusting the volume at each station, a manual controlling switch at one of said stations, a pair of auxiliary signaling circuits interconnecting said stations, means responsive to any degree of adjustment of said switch in one direction to transmit impulses over one of said auxiliary circuits, and means responsive to any degree of adjustment of said switch in the opposite direction to transmit impulses over the other auxiliary circuit, the number of impulses transmitted being determined by the change in the setting of said switch, means at each station responsive to the impulses transmitted over one auxiliary circuit to produce simultaneously an increase in volume at one station and a decrease in volume at the other station, said means responding to impulses transmitted over the other circuit to produce a decrease in the volume at the one station and an increase at the other.
6. In a transmission system, a transmission medium interconnecting two stations, means for adjusting the volume at each station, a manual controlling switch at one of said stations, a pair of auxiliary signaling circuits interconnecting said stations, means responsive to any degree of adjustment of said switch in one direction to transmit impulses over one of said auxiliary circuits, and means responsive to any degree of adjustment of said switch in the opposite direction to transmit impulses over the other auxiliary circuit, the number of impulses transmitted being determined by the change in the setting of said switch, step-by-step means at each station for controlling the volume adjusting means, said step-by-step means being responsive to the impulses transmitted over one auxiliary circuit to increase the volume at one station and decrease it at the other, and said step-by-step means being responsive to impulses transmitted over the other auxiliary circuit to decrease the vol-

ume at one station and increase it at the other.

7. In a transmission system, a transmission medium interconnecting two stations, means for adjusting the volume at each station, a manual controlling switch at one of said stations, a pair of auxiliary signaling circuits interconnecting said stations, means responsive to any degree of adjustment of said switch in one direction to transmit impulses over one of said auxiliary circuits, and means responsive to any degree of adjustment of said switch in the opposite direction to transmit impulses over the other auxiliary circuit, the number of impulses transmitted being determined by the change in the setting of said switch, sets of counting relays at each station for controlling the volume adjusting means thereat, said counting relays operating in response to impulses transmitted over one auxiliary circuit to increase the volume at one station and decrease it at the other and operating in response to impulses transmitted over the other auxiliary circuit to decrease the volume at the one station and increase it at the other.

8. In a transmission system, a transmission medium interconnecting two stations, means for adjusting the volume at each station, a manual controlling switch at one of said stations, a pair of auxiliary signaling circuits interconnecting said stations, means responsive to any degree of adjustment of said switch in one direction to transmit impulses over one of said auxiliary circuits, and means responsive to any degree of adjustment of said switch in the opposite direction to transmit impulses over the other auxiliary circuit, the number of impulses transmitted being determined by the change in the setting of said switch, sets of counting relays at each station for controlling the volume adjusting means thereat, said counting relays at both stations being operated successively in one order in response to impulses transmitted over the one auxiliary circuit to increase the gain at one station and decrease it at the other, and said sets of counting relays being operated in the reverse order in response to impulses transmitted over the other auxiliary circuit to decrease the volume at one station and increase it at the other.

In testimony whereof, I have signed my name to this specification this 11th day of December, 1924.

HUGH F. SHOFFSTALL.
